UNITED STATES PATENT OFFICE

152,433

DESIGN FOR AN ELECTRIC ADVERTISING SIGN FOR VEHICLES

George McGuire Pierce, Los Angeles, Calif.

Application May 23, 1947, Serial No. 139,248

Term of patent 14 years

(Cl. D14—27)

To all whom it may concern:

Be it known that I, George McGuire Pierce, citizen of the United States, residing in the city of Los Angeles, in the county of Los Angeles and State of California, have invented a new, original, and ornamental Design for an Electric Advertising Sign for Vehicles, of which the following is a specification, reference being had to the accompanying drawing, forming part thereof.

Fig. 1 is a perspective view of the electric advertising sign for vehicles, with the cover closed.

Fig. 2 is a perspective view with the cover open.

The other side and the end portions of the sign are similar to what is shown in the drawing figures.

The dotted line showing of a vehicle in the drawing figures is for illustrative purposes only.

I claim:

The ornamental design for an electric adver-

tising sign for vehicles, substantially as shown and described.

GEORGE MCGUIRE PIERCE.
